ABRAM RUPERT NEELANDS AND GEORGES DAMRY, OF DONCASTER, ENGLAND.

CONSTRUCTION OF CONCRETE PILES OR FOUNDATION ELEMENTS.

Application filed April 21, 1925, Serial No. 24,741, and in Great Britain September 25, 1924.

It has been proposed to construct concrete piles or foundation elements by boring a hole in the ground until a stratum of rock, gravel or other suitable supporting material is reached or until the depth of the hole in the ground is sufficient to give a safe bearing area to the pile to be cast later in this hole without necessarily reaching a stratum of rock or solid ground; providing the bore hole 10 with a metal casing which serves as a temporary lining pipe, introducing concrete into the bore hole, and ramming or battering the concrete so that it not only fills the bore hole but is pressed or forced to expand laterally 15 into the ground surrounding the bore hole by the combined action of the ramming operation and the intermittent or continued lifting of the lining pipe, this process being repeated or continued until the pile has been 20 formed.

As the exterior surfaces of piles constructed in this manner are irregularly shaped, according to the nature of the ground in which they are formed, and as 25 their diameter is larger than the diameter of the temporary lining pipe, their bearing capacity is greater than that of piles constructed by other methods. When forming concrete piles of this character, a finished 30 mixture of cement and aggregate, forming a complete concrete is rammed into the bore hole, and, as it has been found that piles constructed in this manner cannot be employed very effectively in very soft and 35 fissured ground as the concrete cannot expand further than the cavity or hole bored or drilled to receive it and the chief object 40 of the present invention is to provide an improved method of forming piles or foundation elements in fissured, soft or heavily water logged ground.

According to the present invention, and in lieu of employing concrete or a finished 45 mixture of cement and aggregate as the filling material, a concrete pile is produced by forming a bore hole, fitting it with a temporary lining tube and injecting liquid cement or the like under pressure into a mass of gravel, ballast or the like previously 50 rammed in place in the ground. By proceeding in this manner a pile can successfully be formed in loose, soft or heavily logged ground intimately welded or fastened into the bore hole containing it and substantially 55 rooted into the surrounding strata.

In constructing the pile according to the

improved method the following procedure may be adopted:—A hole of suitable diameter is bored in the usual and most suitable manner until rock or a suitable supporting material is reached or until the depth of the hole ensures a sufficient bearing area for the pile, a suitable casing tube being placed within the bore hole as boring proceeds or after the completion of the same, according 60 to circumstances. A number of vertically disposed steel tubes of suitable diameter and perforated along their length are now inserted into the bore hole and on the full depth of same. Thereafter clean gravel, ballast or any other suitable material is introduced in limited quantities and rammed in place so that it is forced to expand laterally 65 into the surrounding strata, the casing being lifted intermittently or continuously during 70 the ramming operation.

The ram, which is preferably cylindrical, is perforated vertically with a number of holes, corresponding to the number of upright steel tubes employed, so that the ram 80 is free to slide along the tubes which thus may act as guides during its up-and-down movement. When, for example, the hole has been filled up to ground level with gravel or ballast and after the casing tube has been 85 entirely removed from the hole, liquid cement or a mixture of cement and water in suitable proportions or any suitable matter susceptible of setting later may now be introduced through the perforated tubes by 90 means of a suitable grouting or pumping plant, or by compressed air or any other method.

In order that the said invention may be clearly understood and readily carried into 95 effect the same will now be described more fully with reference to the accompanying drawing which illustrates diagrammatically and by way of example one method of carrying the invention into practice, and in 100 which:—

Figure 1 is a longitudinal section taken on the line *b*—*b* of Figure 2 showing a bore hole ready to receive the ballast.

Figure 2 is a cross section on the line *a*—*a* 105 of Figure 1.

Figure 3 is a longitudinal section of the ballast rammer, the section being taken on the line *c*—*c* of Figure 4.

Figure 4 is a horizontal cross section taken 110 on the line *d*—*d* of Figure 3.

Figure 5 is a longitudinal section taken on

the line *e*—*e* of Figure 6 showing the pile during the course of construction.

Figure 6 is a horizontal cross section taken on the line *f*—*f* of Figure 5.

5 Figure 7 is a longitudinal section showing the bore hole filled with ballast and ready to receive the liquid cement.

Figure 8 is a longitudinal section of the completed reinforced pile, the cement having been forced or injected under pressure

10 into the ballasting and also into the openings and fissures of the surrounding strata.

In this view the tubes through which the liquid cement is injected are shown in section

15 and on an enlarged scale so as to illustrate the perforations clearly through which the cement passes into the ballasting and the surrounding strata.

For the purpose of the example illustrated

20 in the drawing it has been assumed that it is desired to form a reinforced pile in a section of ground comprising the following strata namely, a surface deposit of soil 1,

25 followed by a bed of hard clay 2, and a bed of loose ground, sand, quick sand made up

ground, dry or water bearing strata 3, the latter resting upon a bed of hard rock 4.

5 is the casing tube and 6 is the cutting edge at the lower end thereof. 7, 7 are four tubes which are perforated along their

length with small holes, the tubes being employed for the injection of liquid cement and as reinforcements for the pile. 8 is the

35 rammer fitted at its upper end with a swivelling shackle for attachment to the rope or rod 9 by which the rammer is suspended. The rammer is perforated along its length with four holes 10, 10 of a diameter sufficient

40 to allow the four tubes 7, 7 to pass freely therethrough. The injection tubes 7, 7 are connected to the cementation plant by means

35 of suitable piping 18, 18 flexible or rigid as preferred.

The first operation consists in boring or

45 drilling into the ground where the concrete pile is to be formed a circular hole of a suitable diameter. The method of boring and drilling the hole is chosen according

50 to the nature of the strata and in the example shown the bore hole is deepened until it penetrates a few feet or so into the solid rock 4 on which the base of the pile is to rest. The bore hole is then lined or cased from the ground surface down to the solid

55 rock with the circular casing tube 5, the latter being made of steel, iron or any other suitable material, and may be flush jointed and built up in sections of convenient

60 lengths. The placing of the casing tube 5 in position within the bore hole is carried out either as boring proceeds or after its completion according to the nature of the strata encountered.

65 The boring being completed and an opening having been formed which penetrates a

few feet or so into the solid rock 4, and the steel casing having been located in place, the second operation consists in the construction of the pile in the bore hole which is ready to receive it.

To this end the four hollow and perforated tubes 7, 7 are placed vertically into the bore hole so that they rest upon the bottom of the same.

A certain quantity of ballast is then placed in the bottom of the bore hole, i. e., in that part excavated in the solid rock 4 and this ballast is well rammed in place by means of the rammer 8. The rammer slides freely along the reinforcing bars 7, 7 which consequently act as guides during its up-and-down motion, and the necessary motion is imparted to the rammer by any convenient or suitable method.

The first load of ballast introduced into the bore hole having been sufficiently rammed and compressed the rammer 8 is lifted above ground level in order to allow the introduction of a new load of ballast into the bore hole which in turn is rammed in place, these operations being repeated until the level of the compressed ballast reaches the level of the solid rock, which is also as previously explained the level of the cutting edge of the steel casing 6.

The building up of the reinforced pile is now continued through the loose ground, sand, quick sand or water bearing strata 3 in the following manner:

A new load of ballast is introduced into the bore hole and rammed in place by the rammer 8. As the ramming proceeds the steel tube 5 is lifted to a certain height above the level of the rock 4, this operation being carried on in any suitable manner. On lifting the casing 5 to a suitable height the ballast last introduced into the hole is placed in intimate contact with the surrounding strata, and this fact combined with the continuation of the energetic ramming causes a lateral expansion of the ballast into the loose ground 3 over a height or distance comprised between the level of the solid rock 4 and the bottom of the cutting edge 6 of the steel casing 5. As this lateral expansion progresses new loads of fresh ballast are introduced into the hole until the expanded pile has reached at that level a diameter known calculated or estimated to be sufficient for the purpose.

When the fresh ballast last introduced has been rammed in place and when its expansion has reached the required diameter, a further quantity of ballast is introduced into the bore hole, the casing being lifted higher up and the operations above described being continued until the reinforced and compressed pile has reached the height of the ground level.

In order to maintain the reinforcing bars

7, 7 of the pile at a correct and constant distance apart during the ramming of the ballast into place, ties 13, 13 are introduced into the bore hole and located around the 5 reinforcing bars, the ties being pressed into the fresh ballast last introduced by the action of the rammer.

The perforated tubes 7, 7 are now coupled up to a pumping or grouting plant, 10 and liquid cement is forced along the same. From the perforated tubes the liquid cement penetrates first into the cavities of the gravel or ballast and thereafter is forced under pressure to percolate into the surrounding 15 strata, thus filling with neat cement all the pores, fissures or cavities of the same. Consequently, the ground around the bore hole is consolidated to a considerable extent. When the final quantities of liquid cement 20 are injected the spaces in the gravel or ballast itself are filled up so that it is very closely and intimately embedded into the strengthened surrounding strata, while, in the case of water bearing strata, the water 25 originally present in the strata is expelled to a safe distance from the pile. The liquid cement or other binding material may be forced into the ballast gravel or other filling material at any time either at the completion 30 of the filling of the bore hole as above described or in stages during the filling of the bore hole or continuously and conjointly with the filling in of and ramming of the gravel ballast, &c.

35 The tubes through which the liquid cement has been injected serve as reinforcements for the pile and their upper ends need not be level with the ground but may project to any desired height above this level 40 and be incorporated as reinforcing elements in the buildings, structures or the like erected upon and supported by the piles.

In the drawing Figures 1 and 2 represent the bore hole completed and penetrating to 45 a certain depth into the solid rock 4, the casing tube 5 having been placed in the bore hole in order to prevent the sides thereof from falling in and the cutting edge 6 resting upon the solid rock 4. The four perforated tubes have also been placed into the bore hole.

50 Figures 5 and 6 represent the pile during the course of construction. The bottom part of the hole bored into the solid rock 4 has been filled with ballasting 11, a further quantity of fresh ballasting 12 has been introduced into the bore hole, the casing tube 5 has been lifted to a certain height and the additional quantity of ballasting 12 is being forced to expand into the loose ground 3 by the action of the rammer 8, sliding up and down upon the reinforcing bars 7, 7. Two sets of ties 13, 13 have been fitted around the reinforcing bars at suitable 55 intervals apart and have been pressed into

the fresh ballasting by the action of the rammer 8 in order to maintain the bars 7, 7 at the correct distance apart.

Figure 7 shows the pile after it has been completely filled with ballasting, the ballasting having been expanded to a suitable diameter into the loose soil 3 immediately above the solid rock 4 and tapering off from that level to the base of the solid clay 2 through which clay the pile remains cylindrical. The casing tube 5 has been entirely removed from the bore hole.

Figure 8 shows the completed pile. When the stage shown at Figure 7 is reached the four perforated pipes 7, 7 are coupled up to a pumping or grouting plant and a mixture of cement and water or any suitable setting matter is forced to percolate from the perforated pipes 7^a, 7^a into the spaces between the gravel or ballast and from there into the fissures 17, 17 as also the pores or cavities of the surrounding strata.

It will be clear that the minimum diameter to which the pile must expand at any given level will vary with the total load to 90 be supported by the pile, the nature of the strata at that level and the depth of the pile. It will also be clear that the original diameter of the bore hole, the dimensions of the casing tube, the dimensions and 95 weight of the rammer, the quantity of ballasting introduced at a time into the hole, the height to which the casing tube is lifted at a time, the number of blows given by the rammer for each load of fresh ballasting, as 100 also the dimensions and number of the reinforcing bars are variable quantities which will be modified to suit different circumstances and conditions. The penetration of the pile at its base into the solid rock 4 (when the solid rock is within economical 105 reach of the bore hole) also effects a keying of the pile which prevents any tendency for it to slide upon the surface of the rock when submitted to lateral strains and enables the resistance of the pile to shearing 110 stresses to come into action.

By means of the present invention a more effective rooting or foundationing of the pile into the ground is obtained owing to the 115 fact that the injection of the liquid cement or the like ensures a perfectly watertight joint between the ballast which has been rammed into the hole and the sides of the hole. The pile is also effectively rooted into 120 the surrounding ground owing to the fact that the cement or the like injected into the body of the hole also flows and spreads into the adjacent fissures, channels and cavities in the surrounding ground thus forming a system of lateral supports which are more complicated and more substantially in proportion as the surrounding ground is more open and consequently more weak. The pile, therefore, is more stable, rigid and 125 130

better supported and protected than with any previous known method of constructing piles, and owing to the spreading or lateral extensions of the pile into the surrounding ground the ground is consolidated and strengthened to a substantial extent so that the effective area of supports given by the pile is increased.

What we claim and desire to secure by

10 Letters Patent of the United States is:—

1. A method of constructing concrete piles which consists in forming a bore hole, fitting it with a temporary lining tube, locating perforated tubes in the bore hole, ramming ballasting into the ground and around the perforated tubes, raising the lining tube, and finally injecting liquid cement under pressure through the perforated tubes into the mass of ballasting previously rammed in place in the ground.

2. A method of forming a reinforced concrete pile which consists in forming a bore hole, fitting it with a temporary lining tube, locating a number of vertically disposed 25 perforated steel tubes of suitable diameter therein, ramming a mass of ballasting into the ground and around the perforated tubes, lifting the casing during the ramming operation, and subsequently injecting a binding material through the perforated tubes into the ballasting as also into the surrounding strata.

3. A method of forming a reinforced concrete pile as claimed in claim 1, in which ties 35 are fitted during the operation of forcing the ballasting into place for the purpose of holding the perforated tubes at the correct distances apart.

4. A method of constructing concrete 40 piles, which consists in forming a bore hole, fitting it with a temporary lining tube, locating perforated tubes within the bore hole, ramming ballasting, into the ground and around the perforated tubes by means of a 45 cylindrical mass of metal which is free to slide along the perforated tubes so that the latter act as guides during its up and down movement, raising the lining tube and finally injecting liquid cement under pressure 50 through the perforated tubes into the mass of ballasting previously rammed in place in the ground.

5. A method of constructing concrete piles, which consists in forming a bore hole,

fitting it with a temporary lining tube, locating perforated tubes in the bore hole, placing ballasting, into the lining tube and around the perforated tubes, expanding the said ballasting, into the bore hole by ramming the same while simultaneously 60 raising the lining tube, and finally injecting a binding material under pressure through the perforated tubes into the mass of ballasting previously rammed in place in the ground.

6. A method of constructing concrete 65 piles, which consists in forming a bore hole, fitting it with a temporary lining tube, locating perforated tubes in the bore hole, placing ballasting into the lining tube and around the perforated tubes, expanding the 70 said ballasting into the bore hole by ramming the same while continuously raising the lining tube and finally injecting liquid cement under pressure through the perforated tubes into the mass of ballasting previously rammed in place in the ground.

7. A method of forming a reinforced concrete pile which consists in forming a bore hole, fitting it with a temporary lining tube, locating a number of vertically disposed 80 perforated steel tubes of suitable diameter therein, locating ballasting in the lining tube and around the perforated tubes, expanding the said ballasting into the bore hole by ramming the same and by continuously lifting the casing during the ramming operation, and subsequently injecting a binding material through the perforated tubes into the ballasting as also into the surrounding strata.

8. A method of constructing concrete 90 piles, which consists in forming a bore hole, fitting it with a temporary lining tube, locating perforated tubes within the bore hole, placing ballasting into the lining tube and 95 around the perforated tubes, expanding the ballasting into the bore hole by ramming the same by means of a cylindrical mass of metal which is free to slide along the perforated tubes so that the latter act as guides 100 during its up and down movement, continuously raising the lining tube during the ramming action and finally injecting liquid cement under pressure through the perforated tubes into the mass of ballasting previously rammed in place in the ground.
